UNITED STATES PATENT OFFICE.

MICHAEL M. CALLAGHAN, OF COLUMBIA, NEVADA.

MINE-BUCKET-DUMPING ATTACHMENT.

No. 884,363.

Specification of Letters Patent.

Patented April 14, 1908.

Application filed September 19, 1907. Serial No. 393,676.

To all whom it may concern:

Be it known that I, MICHAEL M. CALLAGHAN, citizen of the United States, residing at Columbia, in the county of Esmeralda and State of Nevada, have invented certain new and useful Improvements in Mine-Bucket-Dumping Attachments, of which the following is a specification.

This invention relates to mining and excavating work generally and more particularly in its present adaptation to the prospecting and development work of mining.

In hoisting from a mine shaft, it has heretofore been customary to hoist the bucket perpendicularly from the collar of the shaft, and has been necessary to employ a man at the collar of the shaft to swing the bucket to one side so as to permit it to be dumped without any of the soil and water running back into the shaft, a part of such man's duties being the closing of a door at the collar of the shaft so as to protect the workmen in the shaft from the liability to injury from any of the material in the bucket falling back into the shaft. As noted, this work of looking after the doors and removing the bucket to one side requires the services of at least one man.

It is the primary object of my invention to provide a bucket hoisting mechanism which will do away with the necessity of the doors at the collar of the shaft and the services of the man, or men, at such collar required to swing the bucket to one side preparatory to dumping the same, and to this end, the invention consists essentially in a gallows frame embodying bucket guiding and dumping mechanism which will deflect the bucket in its upward traverse from the shaft collar and carry it to one side, the required or predetermined distance, automatically in the operation of hoisting and to also provide means for permitting the bucket to automatically dump itself after being hoisted, to be held securely to one side of the mine shaft until it is desired that it shall be again lowered into the latter, and to provide means whereby the bucket may be released from the holding means and expeditiously lowered into the shaft, all as will be hereinafter fully described and claimed.

For a full understanding of the invention, reference is to be had to the following description and accompanying drawings, in which:

Figure 1 is a sectional side elevation illustrating the invention; Fig. 2 is a detail per-

spective view of parts of the apparatus; Fig. 3 is a fragmentary elevation of a portion of the apparatus, illustrating the mine bucket in the proper position for riding upon its beams; and, Fig. 4 is a detail side elevation illustrating trip devices arranged to permit the bucket to pass downwardly again into the shaft after it has been dumped.

Corresponding and like parts are referred to in the following description and indicated in all the views of the drawings by the same reference characters.

Referring to the drawings, the numeral 1 designates the lining of a shaft above which the gallows frame is mounted. This frame may be constructed in various ways, so far as its general structure for supporting purposes is concerned and in the present instance it embodies the sills 2, uprights 3, cross beams 4, upper longitudinal beams 5 supported on the upper ends of the posts or uprights 3, and the braces 3^a secured to two of the posts and to extensions of the sills 2.

The shaft lining 1 is provided at opposite sides with the vertical rails 6 which, in the present instance, join at the collar of the shaft, the lower ends of inclined rails supported within the framework and carried off obliquely at the desired angle and to the required height according to the requirement of the case and the size of the framework.

A cross head 8 is mounted for movement along the rails 6 and inclined rails 7 of my invention, said cross head preferably embodying spaced beams 9 that are formed with openings 10 through which the hoisting cable 11 passes. Preferably, also, the cross head 8 is formed with rollers 12 to reduce friction, and to insure the positive and easy traverse of the cross head from the vertical portions of the rails to the inclined portions thereof, and vice versa.

The cable 11 passes over the sheave 13 journaled in the longitudinal beams 5 at the top of the framework and may be secured at one end to any windlass or hoisting mechanism. The bucket 14 has its bail 15 secured to the other end of the cable 11 and preferably the said cable is provided with a stop 16 of any desired construction, designed to limit the independent movement of the cable through the cross head at the required point, it being the purpose of the cross head to steady the bucket in its passage up and down the shaft.

Underneath the inclined rails 7, inclined

bucket supporting beams 17 are secured within the framework. The upper shaft sheave 18 at the collar of the shaft is journaled between the lower ends of these bucket supporting beams 17 and the cable is designed to pass over such sheave, in the customary way. The bucket 14 is provided, preferably near its bottom with diametrically opposite outwardly projecting arms 19 designed to slide 10 along the beams 17 as the bucket is raised and lowered within the framework. At the upper end of the shaft lining 1 inclined deflectors 20 and 21 are secured, said deflectors being arranged in substantially V-shape, as 15 shown, with a space between their lower ends and with their upper ends contiguous to the lower ends of the respective bucket supporting beams 17, the space between said deflectors being provided as a passage for the hoisting cable, and one of said deflectors being 20 preferably longer than the other, so as to prevent either of the arms 19 of the bucket from wedging in between the said deflectors. It is the function of these deflectors to engage 25 either one of the arms 19 of the bucket, as the latter is being hoisted, so as to positively turn the bucket into a position where its two arms will engage with and slide along the beams 17. The beams 17 are provided at their 30 lower ends with ledges 22 of sufficient width to support the bucket between them, but beyond these ledges the beams 17 are set far enough apart to permit the bucket to drop between them and swing freely on the arms 35 19. The beams 17 are provided above the ledges 22 with sockets 23 and with side recesses 24 contiguous to said sockets, trips 25 being pivoted within the recesses with their lower ends weighted so as to swing normally 40 into a position where their upper ends will project above the slide surfaces of the beams.

In the practical operation of my improved hoisting mechanism and bucket dumping attachment therefor, from the foregoing description in connection with the accompanying drawings, it is manifest that when the cross head is drawn upward from the collar of the shaft, it will move along the inclined rails 7 to one side of the shaft opening, while 45 the bucket itself will be drawn up over the ledges 22 and along the bucket supporting beams 17, the arms 19 of the bucket resting on said beams. The bucket will thus be carried to one side of the shaft and when the arms 19 register with the sockets 23, it is obvious that the hoisting cable may be slightly slackened so as to permit the bucket to automatically discharge its contents. As the arms 19 lodge in the sockets 23, the bucket 50 will be held in the elevated position at one side of the shaft without any danger of its sliding back into the shaft until it is desired that it shall be lowered. For the lowering operation, it is only necessary to pull the bucket upwardly beyond the sockets 23

which will cause the arms 19 to pass upwardly over the upper ends of the trips 25. As soon as this has been accomplished, the bucket may be lowered, and in passing backwardly over the upper ends of the trips, it 70 will be deflected from the sockets and permitted to slide downwardly along the beams and into the shaft.

It will thus be seen that I have provided a very simple, durable and efficient construction of gallows frame for mining and excavating work generally in which the bucket, as it is hoisted, will be automatically carried to one side of the mouth of the shaft where it may be permitted to discharge its contents 75 without the necessity of employing a laborer to tip it where the contents will be dumped where there will be no liability of their dropping or falling back into the shaft, and without the necessity of employing a man or men at the collar of the shaft to carry the bucket to one side and also without the necessity of employing the doors at the collar of the shaft to close the same, thereby effecting a saving 80 in the maintenance and operation of the apparatus as well as enabling the work to be done more quickly and with more precision than would otherwise be the case.

Having thus described the invention, what is claimed as new is:

1. An apparatus of the character described, comprising a framework designed for location at the collar of a shaft, inclined rails supported in said framework, a cross head mounted to move along said rails, a 95 bucket, and a hoisting cable secured to said bucket and adapted to be connected to the cross head whereby the bucket as it is hoisted from the shaft and carried upwardly in the framework, will be deflected to one side of the shaft opening.

2. An apparatus of the character described, comprising a framework adapted to be located at the opening of a shaft, inclined rails mounted in the said framework, a cross head mounted to move along said rails, a bucket, a hoisting cable secured to said bucket and passing through said cross head, and inclined bucket supporting beams mounted in the framework underneath the said rails, the bucket being adapted to slide along said beams as it is carried upwardly, and the beams being provided with means for supporting the bucket in an elevated position within the framework.

3. In an apparatus of the character described, the combination with a shaft, of a framework mounted thereabove, inclined rails mounted in said framework and with their lower ends contiguous to the mouth of the opening of the shaft, a cross head mounted to move along said rails, a bucket, a hoisting cable adapted to raise the cross head and bucket, and inclined bucket supporting beams mounted in the framework and below

the rails, said beams being provided at elevated points within the sockets, and the bucket being provided near its bottom with outstanding arms adapted to slide along the 5 beams and lodge in said sockets, the beams being wide enough apart to permit the bucket to swing between them on the said arms.

4. In an apparatus of the character described, the combination of a shaft lining 10 provided at opposite sides with rails, a framework mounted at the upper end of the lining, inclined rails mounted in said framework and forming a substantial continuation of the shaft rails, a cross head mounted to 15 move along said rails, a bucket, a hoisting cable secured to the bucket and adapted to draw the cross head and bucket upwardly from the shaft and in the framework, the bucket being provided near its bottom with 20 outstanding arms, inclined bucket supporting beams mounted in the framework underneath the inclined rails, said beams being provided near their lower ends with ledges adapted to support the body of the bucket, 25 and being large enough above said ledges to permit the bucket to swing between them, the arms of the bucket being adapted to slide along said beams, and the beams being formed at elevated points with sockets adapt- 30 ed to receive said arms.

5. An apparatus of the character described, comprising a framework adapted to be supported at the upper end of a shaft, inclined bucket supporting beams mounted in 35 said framework with their lower ends contiguous to the shaft, deflectors extending downwardly from the lower end of said beams, said deflectors converging toward their lower ends, a bucket provided with outstanding 40 arms, means for hoisting the bucket along the beams with the arms sliding on the upper surfaces of the beams, the deflectors being adapted to turn the bucket so as to insure the registry of the arms and the beams, and 45 means for permitting the bucket to swing between said beams in an elevated position.

6. An apparatus of the character described, comprising a framework adapted to be located at the upper end of a shaft, inclined bucket supporting beams mounted in 50 said framework, a bucket provided with outstanding arms adapted to slide along the up-

per surfaces of the beams, a hoisting cable secured to said bucket, and deflectors extending downwardly from the lower ends of 55 said beams and converging at their lower ends with a space between them for the passage of the hoisting cable.

7. An apparatus of the character described, comprising a framework adapted to 60 be located at the upper end of a shaft, inclined bucket supporting beams mounted in said framework, a bucket provided with outstanding arms adapted to slide along the upper surfaces of the beams, a hoisting cable 65 secured to said bucket, and deflectors extending downwardly from the lower ends of said beams and converging at their lower ends with a space between them for the passage of the hoisting cable, one of said deflectors extending downwardly to a lower point than the other, as and for the purpose set forth.

8. An apparatus of the character described, comprising a supporting framework, 75 inclined bucket supporting beams mounted in said framework and provided with sockets, a bucket provided with outstanding arms adapted to slide along the upper surfaces of said beams and fall into said sockets, means 80 for hoisting the bucket along the beams, and pivoted trips connected to the beams above and close to the said sockets, with one end normally projecting above the upper surfaces of the beams, as and for the purpose set 85 forth.

9. An apparatus of the character described, comprising a framework designed for location at the collar of a shaft, inclined beams supported in said framework, a bucket 90 provided near its bottom with outstanding arms adapted to slide along said beams, the bucket being arranged to swing between the beams, and a hoisting cable adapted to draw the bucket upwardly and laterally along the 95 beams, the beams being provided with sockets for the reception of said arms, as and for the purpose set forth.

In testimony whereof I affix my signature in presence of two witnesses.
